UNITED STATES PATENT OFFICE

169,783

WARM AIR RESIDENTIAL FURNACE

Kenneth R. Phillips, Seattle, Wash.

Application October 11, 1952, Serial No. 21,806

Term of patent 14 years

(Cl. D81—1)

To all whom it may concern:

Be it known that I Kenneth R. Phillips, a citizen of the United States, residing at Seattle, Washington, has invented a new, original, and ornamental Design for a Warm Air Residential Furnace, of which the following is a specification, reference being had to the accompanying drawings, forming a part thereof, in which

Figure 1 is a perspective view of a warm air residential furnace, showing my new design;

Figure 2 is a top view;

Figure 3 is a side elevational view showing the side opposite that shown in Figure 1; and

Figure 4 is an end elevational view showing the end opposite that shown in Figure 1.

I claim:

The ornamental design for a warm air residential furnace, as shown.

KENNETH R. PHILLIPS.
